UNITED STATES PATENT OFFICE.

CHARLES E. JEWELL, OF AUBURN, NEW YORK.

TRUSS.

1,218,664.

Specification of Letters Patent. Patented Mar. 13, 1917.

Application filed April 17, 1916. Serial No. 91,508.

To all whom it may concern:

Be it known that I, CHARLES E. JEWELL, of Auburn, in the county of Cayuga and State of New York, have invented certain new and useful Improvements in Trusses; and I do hereby declare the following to be a full, clear, and exact description of the same, reference being had to the accompanying drawings, forming a part of this specification, and to the reference-numerals marked thereon.

My invention relates to trusses such as are used in the treatment of hernia and similar diseases, and has for its chief purpose to provide a novel construction and arrangement of parts that readily permits of proper adjustment, so as to intimately engage the spot or area of the body to be treated, and to effect the necessary amount of pressure, while at the same time permitting a nice resiliency or yieldability of the engaging pad in order to accommodate any position of the body without discomfort. Another object of my invention is to afford a structure that can be worn with comfort and ease, and shall be both of light weight and sanitary. A further purpose of the invention is to afford an improved means for holding the pressure pad at all times in proper relation to the body after it is once adjusted. To these and other ends the invention resides in certain improvements and combinations of parts, all as will be hereafter more fully described, the novel features being pointed out in the claims at the end of the specification.

In the drawings:

Figure 1 is a front elevation showing the application of the invention in approximately the position in which it may be used;

Fig. 2 is a horizontal sectional view through the pad;

Fig. 3 is a vertical sectional view;

Fig. 4 is an edge elevation of the retaining member;

Fig. 5 is a plan view of the pad, and

Fig. 6 is a plan view of the retaining member.

Similar reference characters throughout the several views indicate the same parts.

In the structure of the present embodiment, 1 designates a belt to be attached around the waist and provided at its ends with the loops 2 adapted to be secured to the opposite ends of a leaf spring 3 which is preferably slightly curved or bowed and

provided with heads or projections 4 to receive said loops 2. The spring 3 is connected by parts which I will now describe, with the pad 5, which is adapted to be positioned against the body so as to engage the affected area or surface. The pad 5 is of the usual form, embodying a filling material 6 surrounded by a leather covering 7, while 8 is a metallic or other rigid plate upon which is pivotally mounted a curved leaf spring 9 that permits the pad to have rotative adjustment so as to be brought into varying relationship with the body. The spring 9 carries at its ends pivoted loops or connections 10 which receive the aforesaid spring 3, thereby permitting said springs to be flexed with relation to each other and also permitting relative endwise movement. The spring 9 which is directly connected to the pad is bowed outwardly or with its ends extending outwardly in a direction away from the pad, while the spring 3 is preferably bowed slightly in the opposite direction, as indicated in full lines in Fig. 2, thereby affording the necessary resiliency of action when pressure is applied to move the springs to the position shown in dotted lines, while at the same time maintaining the required pressure upon the pad.

The particular arrangement of springs which I have shown contribute to afford an extremely efficient support for the pad, which is always held by a constant, even pressure, and permits perfectly free movement of the body under all conditions, without affecting the proper action of the pad.

In trusses of this general type, it has been usual to employ a supplemental strap passing downwardly, and between the legs, from the front to the rear of the belt, in order to prevent the latter from working upwardly about the body and it is my purpose to eliminate the use of such supplemental retaining strap, and to substitute a more effective and more advantageous means for retaining the pad in proper position, which is accomplished in the following manner. 11 designates a retaining member which may be in the form of a plate of leather or other flexible material of suitable configuration and adapted to be adhesively secured to the body. To this end, the retaining member may be provided on its interior surface with an adhesive portion 12, which is first positioned over the spot to which the truss pad is to be applied and retained there by the

action of the adhesive material. The retaining member 11 is detachably connected with the truss pad 5 preferably by a bend and socket joint, although any other detachable connection may be successfully employed. The retaining member 11 carries a plate 13 on which is formed a head or projection 14 arranged to engage a socket on the pad. For this purpose, the latter has secured to its operative face a metal plate 15, provided with an opening 16, enlarged at one end to receive the head 14, and reduced at the other end in order to hold the head 14 against relative displacement. With this arrangement, when the pad is positioned in the manner shown in Fig. 1, upward movement thereof is prevented by reason of the engagement of the head 14 with the lower end of the opening 16, while to remove the parts, it is only necessary to push the pad slightly in a downward direction to bring the large end of the opening 16 opposite to the head 14, after which the pad and retaining member can be separated. The retaining member can be removed from the

body if desirable when the pad is removed, and the adhesive surface 12 can be renewed as often as required.

I claim as my invention:

1. The combination with a truss pad, and body encircling means for applying pressure to the pad, of a retaining member adapted to be adhesively secured to the body of a person, and a detachable connection between the truss pad and said retaining member.

2. The combination with a truss pad, of a retaining member adapted to be adhesively secured to the body of a person, a socket in the truss pad, and an enlargement or head on the outer face of said retaining member for detachable engagement with said socket.

3. The combination with a truss pad, and means for supporting it, of a retaining member therefor adapted to be adhesively secured to the body of a person.

CHARLES E. JEWELL.
